PORTABLE LAMP

Hajime Ota, Tokyo, Japan, assignor to Fedtro, Inc., a corporation of New York

Filed Oct. 22, 1965, Ser. No. 87,775

Term of patent 3½ years

(Cl. D48—24)

FIG. 1

FIG. 2

FIG. 6

FIG. 4

FIG. 5

FIG. 1 is a front elevational view of a portable lamp showing my new design;

FIG. 2 is a rear elevational view;

FIG. 3 is a right side view;

FIG. 4 is a left side view;

FIG. 5 is a top plan view; and

FIG. 6 is a bottom plan view thereof.

I claim:

The ornamental design for a portable lamp, substantially as shown.
